(57) **CLAIM**

The ornamental design for a container ring as shown and described.

DESCRIPTION

FIG. 1 is a top perspective view of a container ring showing our new design;

FIG. 2 is a bottom perspective view thereof;

FIG. 3 is a top view thereof;

FIG. 4 is a bottom view thereof;

FIG. 5 is a side view thereof; and,

FIG. 6 is a cross-sectional view thereof, taken along line 6-6 in FIG. 3.

The dot-dash broken lines represent the designation of an enlarged cross-sectional view and form no part of the claimed design.
